INDIRECT GAS-FIRED OVEN

Albert M. Sage, Belleville, N. J., assignor to
Steiner-Ives Co., Newark, N. J., a corporation of
New Jersey

Application October 5, 1945, Serial No. 620,555

2 Claims. (Cl. 263—15)

1

My invention is directed toward a highly improved construction for industrial ovens of the indirect gas-fired type adapted for the use of baking dipped or sprayed paint or enamel coatings on metal parts, impregnated electric coils, the curing of rubber products and for all other drying or similar processes requiring the application of clean, heated air at uniform temperatures, automatically controlled.

One of the objects of my invention is the provision of a novel heater unit designed for use with an industrial oven of the character herein described which shall be so constructed and arranged as to be unaffected by variations in atmospheric pressure in the room in which the oven is stationed to thereby prevent back-drafts from causing over-heating of the burner and consequent failure of the oven due to the forming of carbon which is deposited in the combustion chamber.

Another object of my invention is to provide an indirect gas-fired oven and heater unit of the character described which shall be so designed that the products of combustion from the gas burner are prevented from coming in contact with the work being processed in the oven.

Still another object of my invention is the provision of an indirect gas-fired oven and heater unit of the character described which shall contain novel and improved constructional features representing a general advance in the art.

Other objects of my invention will hereinafter be pointed out or will become apparent from the description to follow.

In the accompanying drawings,

Fig. 1 is a perspective view of an indirect gas-fired oven and heater unit constructed and arranged in accordance with my invention;

Fig. 2 is a longitudinal vertical cross-sectional view of the apparatus shown in Fig. 1;

Fig. 3 is a top plan view of a portion of the apparatus shown in Figs. 1 and 2;

Figs. 4 and 5 are cross-sectional views taken substantially along the lines 4—4, of Fig. 3 and 5—5 of Fig. 4, respectively;

Figs. 6, 7, 8 and 9 are cross-sectional views taken substantially along the lines 6—6, 7—7, 8—8 and 9—9 respectively of Fig. 5;

Fig. 10 is an enlarged view of a portion of the duct wall shown in Fig. 6; and

Fig. 11 is a front elevational view thereof.

Referring now in detail to the drawings, I have illustrated an industrial oven 10 of the indirect gas-fired type and a heater unit 50

2

mounted thereon both being constructed and arranged in accordance with my invention. The said oven 10 comprises a pair of side walls 11 and 12, a top wall 14 and a bottom wall 15 forming a rectangular baking compartment 20 adapted to receive therein articles to be baked or processed. A pair of suitably constructed and hingedly mounted doors 16 form the front wall and a similar pair of doors 17 form the rear wall of the said baking compartment 20. The doors 16 and 17 are so constructed as to form a heat seal with the walls 11, 12, 14 and 15 to prevent heat loss from the baking compartment when the oven is in effective use.

To facilitate the placing and removal of articles, to be baked, into and out of the baking compartment 20, there may be provided two pairs of channel tracks 21 and 22, set into the bottom wall 15, to serve as guides for any suitable type of article carrying oven trucks, well known to the art. It is noted that portions of the tracks 21 and 22 extend beyond the front and rear walls 16 and 17 of the oven, the said extending track portions terminating in outwardly flared ends to more readily guide the trucks into and out of the oven.

To reduce heat loss from the baking compartment through the walls and doors to a minimum, the walls 11, 12, 14, 15 and the doors 16 and 17 may each comprise a pair of spaced steel plates with mineral wool insulation between the plates, as clearly shown in Fig. 2 of the drawings.

As a measure of safety, pressure relief covers 35 24 may be provided in the top wall 14, the said covers 24 being similar in construction to that of the wall 14 and fitted to prevent heat loss from the oven.

Spaced from the side wall 11 a predetermined distance and parallel thereto is an auxiliary wall 25 of metallic material forming an air duct 30 between the said walls 11 and 25, the said duct 30 being substantially coextensive with the said side wall 11. Spaced from the side wall 12 a predetermined distance and parallel thereto is an auxiliary wall 26 of metallic material forming an air duct 31 between the said walls 12 and 26, the said duct 31 being substantially coextensive with the said side wall 12. The walls 25 and 26 are provided with a plurality of apertures 27 and 28 respectively communicating directly with the ducts 30 and 31 and the baking compartment 20. The apertures 27 in the wall 25 are designated as inlet ports and the apertures 28 in the wall 26 as outlet ports. In accordance with my invention

and by means which will soon be described, heated air from the heater unit 50 is forced into the duct 30 and through the inlet ports 27 into the baking compartment 20, where the said heated air acts upon the articles to be baked or processed, after which it will be drawn into the duct 31 through the outlet ports 28 and out of the duct 31 to be recirculated.

Heated air is supplied to the baking compartment by means of a heating unit 50, now to be 10 described.

The said heating unit 50 comprises a rectangular-shaped casing made up of the top wall 51, bottom wall 52, side walls 53 and 54, front wall 55 and rear wall 56. Each of the said walls of the heater unit except the bottom wall 52, which is adjacently disposed to the top wall 14 of the oven, may comprise a pair of spaced steel plates, with mineral wool insulation between the plates, similar in purpose and function to the hereinbefore described construction of the walls of the oven. The bottom wall 52 of the heater unit 50 may be a steel plate and the entire unit 50 is mounted on the top wall 14 of the oven by means of the angles 57 and 58 which may be welded to the side walls 53 and 54 and to the said top wall 14, in such manner as to provide a space 60 between the said bottom wall 52 and the top wall 14, as clearly shown in Figs. 2, 4, and 6 to 9 of the drawings.

The interior of the heater unit 50 is provided with an auxiliary wall 61 parallel to and spaced from the top wall 51; an auxiliary wall 62, parallel to and spaced from the side wall 54 and an auxiliary wall 63 parallel to and spaced from the rear wall 56, the said auxiliary walls 61, 62 and 63 serving to divide the heater unit into two compartments 65 and 66, independently sealed off from each other, the compartment 65 serving as the combustion chamber and the compartment 66 serving as the air chamber. The air chamber 66 is provided with a blower compartment 68, housing a suitable blower device 70 of any standard type suitable for the purposes intended.

Disposed in the combustion chamber 65 and sealed off from direct communication therewith by the vertical walls 71 and 72 is an air duct 13 which communicates directly with the duct 30 by means of an opening 74 in the bottom wall 52 of the heater unit 50 and an aligned opening 75 in the top wall 14 of the oven, as clearly noted in Figs. 5 and 7.

As noted in Figs. 5 and 6 of the drawings, in that portion of the bottom wall 52 of the heater unit 50, constituting the air chamber 66, there is provided an opening 59 communicating directly with the duct 31 in the oven 10, and which as noted in the drawings extends upwardly through an opening in the top wall 14 of the oven.

Mounted between the wall 72 of the duct 13 and the wall 63 of the combustion chamber 65 are a plurality of heat exchange pipes 80. It is noted that the pipes 80 are so arranged that they communicate directly with the duct 73 at one end and the blower compartment 68 at the other end, the said pipes being disposed within the combustion chamber 65 and independently air sealed therefrom.

It is thus seen from the above described construction that when the blower 70 is in operation, air will be drawn by suction from the baking compartment 20 via the duct 31 and the air chamber 66, into the blower 70 through the opening 81 in the wall 82 of the blower compartment. It will then be forced through the pipes 80, into

5 the duct 73 and thence down into the duct 30 from where it will enter the baking compartment through the inlet ports 27, to provide a continuous circulatory air system passing through the baking compartment 20.

A suitable motor M supported on the wall 53 in any manner well known to the art, drives the blower shaft 70a through the pulleys 84 and 85 on the motor shaft and blower shaft 70 respectively and the interconnecting belt 86.

The following means are employed for heating the air in the above described circulatory system.

A burner or burners of any suitable design may be employed, such as for example, a pair of ribbon type pipe burners 88 passing through the front wall plate 55a and into the combustion chamber 65 extend horizontally substantially the entire length of said combustion chamber to which there is supplied gas from a source of supply, not shown. A mixer 89 of any well known standard type furnishes the proper mixture of air from the surrounding atmosphere with the gas before it enters the said burners 88. A suitable gas pilot burner 90 of the spark ignition type, well known to the art, is mounted on the plate 55a as shown in Fig. 6.

In accordance with my invention, I provide an exhaust fan 92 mounted in an exhaust duct 93, which in turn is mounted in the wall 53. An opening 94 in the casing communicates directly with the combustion chamber 65. When the exhaust fan 92 is operated the heated air in the combustion chamber 65, together with the products of combustion, are drawn out of the said chamber 65 and carried away through the duct 93. It is noted that the pipes 80 are disposed directly in the path of movement of these exhausted products of combustion so that the said pipes 80 will be heated thereby. This will result in heating the air being recirculated through the said pipes 80. It is thus seen that the air supplied to the ducts 73 and 30 and passing horizontally across the baking compartment 20 of the oven is heated to a predetermined degree, depending upon the needs of the articles undergoing processing.

It is also seen from the above, that in accordance with my invention that I provide a separate and positive exhaust for all the products of combustion and that the suction of the exhaust fan creates a negative pressure in the combustion chamber which draws in sufficient primary air through the gas-air mixer of the burners to support complete combustion. By 55 such construction and arrangement the combustion chamber is completely sealed off from the surrounding air in the room, with the result that the burner flames are highly stable in character and are unaffected by changes in the atmospheric pressure of the surrounding air in the room which may be caused by the intermittent operation of exhaust ventilating fans, spray booth fans, etc. which tend to cause "pop backs" and back drafts in the type of ovens heretofore manufactured which rely on natural convection for draft from the burners.

The exhaust fan 92 may be driven from the motor M through the pulleys 95 and 96 on the motor shaft and exhaust fan shaft respectively and by the interconnecting belt 97.

To provide a positive pressure discharge of a certain portion of the air and fumes from the articles processed, there is provided an exhaust stack 100 leading directly from the blower 70 to 75 and passing through the wall 51 (see Fig. 4) to

the atmosphere outside of the oven. The said exhaust stack 100 may be provided with a regulating damper 101 of the type having segments cutout to prevent full closing and to insure a safe minimum ventilation at all times, the balance of the discharge from the blower being forced through the tubes 80 to be recirculated as above described. Constant air flow and uniformity of temperature in all parts of the baking compartment may be obtained by adjustment of the inlet and outlet ports 27 and 28.

To compensate for the air exhausted through the stack 100 fresh air from the atmosphere surrounding the oven is admitted to the air chamber 66 through an inlet opening 105 in the bottom wall 52, to be subsequently drawn in to the blower to join the stream of recirculated air.

The inlet opening 105 communicates directly with the space 60 between the walls 52 and 14, which in turn is open at the ends to the surrounding atmosphere, as shown in Fig. 4. It is noted that the fresh make-up air is thus pre-heated by contact with the walls of the combustion chamber before it enters the recirculating stream.

Certain customarily employed electrically controlled safety measures may be employed so that the burners cannot be lighted unless the motor switch is on. Also certain similar well known means may be employed so that the burners 88 cannot be lighted unless the exhaust fan 92 is running. A suitable glass covered sight opening 110 may be provided in the front wall 55 of the heater unit.

The inlet and outlet ports 27 and 28 respectively, in the duct walls 25 and 26, are preferably constructed as shown in Figs. 10 and 11 of the drawings. A less than 360 degree circular slit is made in the wall 25 of the duct leaving a portion 27b uncut. The said duct wall 25 is preferably of bendable material and the portion 27a within the slit is manually bent away from the plane of said wall 25 to provide an opening 27 the size of which is determined by the amount which the said portion 27a is angularly bent. While in Figs. 10 and 11 I have illustrated the inlet ports 27, it is understood that the outlet ports 28 are similarly constructed.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other means. Also, while it is de-

signed to use the various features and elements in the combination and relations described, some of these may be altered and others omitted without interfering with the more general results outlined, and the invention extends to such use.

Having described my invention, I claim as new and desire to secure by Letters Patent:

1. In an indirect gas fired oven of the character described an independent heater unit having a combustion chamber, a gas burner in said combustion chamber and a gas-air mixer associated therewith, a baking compartment, an air inlet and an air outlet, said last named air inlet and outlet each communicating with said baking compartment and said heater unit, a plurality of heat exchange pipes directly in said combustion chamber and air sealed with respect thereto, and a recirculating blower, each of said heat exchange pipes communicating at one end with said blower and at the opposite end with said air outlet, means for rendering said blower effective to draw air from said baking compartment through said air inlet and to force the same through said heat exchange pipes to be heated thereby and thence through said air outlet into said baking compartment to pass therethrough to be again drawn out through said air inlet by said blower and recirculated, and means comprising an exhaust fan communicating directly with said combustion chamber to produce a negative pressure therein so that sufficient primary air will be drawn in through the gas-air mixer and through the burner to support complete combustion.
2. An indirect gas fired oven according to claim 1 in which the said heat exchange pipes are arranged near one wall of said combustion chamber and in which said exhaust fan communicates directly with the interior of said combustion chamber through an opening in said last named wall so that the products of combustion exhausted by said exhaust fan will pass over said heat exchange pipes to heat the same.

ALBERT M. SAGE.
